THRESHOLD LOCK

Filed April 25, 1947

UNITED STATES PATENT OFFICE

2,553,732

THRESHOLD LOCK

Willis L. Young, Chicago, Ill.

Application April 25, 1947, Serial No. 743,792

2 Claims. (Cl. 292—288)

1

This invention relates to auxiliary locking devices, particularly for outside doors, in addition to the usual latch or lock associated with the door knob, and in particular, includes a bar adapted to be positioned between the lower end of the door and threshold, which is provided with stops on the inner end positioned to contact the inner surfaces of the door, and threshold, and means on the outer end adapted to be secured in a base element by a padlock to contact the outer surfaces of the door and threshold.

The purpose of this invention is to provide a threshold lock for doors, wherein a door may be locked on the outside without having elements or devices attached to the door, door frame, threshold or floor.

The usual door is provided with a pin or tumbler lock, and whereas it is difficult to pick or open locks of this type, they are subject to being opened with skeleton keys and different combinations of pins and devices; and, because tenants receive keys from landlords or their agents and because previous tenants have had keys which may or may not have been returned to the landlord, it is often possible that duplicate keys are in the hands of unauthorized persons; and, because of numbers of other designations sometimes put on keys and locks, and various ways of making impressions of keys, and human factors involved in the making of keys and the changing of locks, it is often possible for burglars, holdup men, hoodlums, detectives, snoops and other unauthorized persons to obtain duplicate keys and enter doors without permission.

With this thought in mind, this invention contemplates an auxiliary lock adapted to be used in combination with the usual door lock, wherein it is also necessary to pick or force an additional and readily changeable lock in order to open a door. The invention is adapted for quick changing of padlocks and is particularly adapted for use of a keyless combination padlock, the combination of which may be easily changed by the user. It is further contemplated that use of an easily changed padlock, or particularly, a changeable combination padlock readily gives the user of a threshold lock additional and more secret means of locking a door.

The object of this invention is, therefore, to provide additional and readily changeable locking means for doors and the like in which the locking device is used in combination with a threshold; and, as attachments and other permanent installations are sometimes not desired or permitted on door frames or door, and in

2

order to avoid obstructions of any kind on the floor, the locking elements are so arranged that the parts thereof are not attached to the door frames, door, threshold or floor.

5 Another object of the invention is to provide a threshold lock using a padlock wherein the padlock may be changed in a few moments.

Another object of the invention is to provide a threshold lock that may use a keyless padlock, 10 the combination of which may be changed in a few moments.

Another object of the invention is to provide a threshold lock that may only be used as desired.

Another object of the invention is to provide 15 a threshold lock that may readily be removed and used on another door.

Another object of the invention is to provide a threshold lock that may be readily positioned in locking relation with a door threshold.

20 Another object of the invention is to provide a threshold lock that may be readily used on a door having no lock or a defective lock.

Another object of the invention is to provide 25 a threshold lock that is easy to construct and economical to manufacture.

Another object of the invention is to provide a threshold lock that may be applied without tools.

Another object of the invention is to provide 30 a threshold lock that may readily lock a door against even authorized persons having keys.

Another object of the invention is to provide a threshold lock that may, if used with a readily changeable combination padlock, guarantee the 35 greatest possible locking secrecy by eliminating all outside human factors.

With these and other objects in view, the invention embodies a substantially horizontally positioned bar with an adjusting thumb screw in 40 the inner end, a door stop also having a thumb screw therein and also positioned on the inner end of the bar, a chain attached to the inner end providing supporting means therefor, a locking element adapted for positioning on the outside of

45 the door with a plate hinged thereto having a spline positioned to extend through a slot in the outer end of the bar, an upwardly extending staple on the base of the locking element positioned to register with a slot in the hinged element thereof, and a padlock adapted to be locked in said staple.

Other features and advantages of the invention will appear from the following description, taken in connection with the drawings, wherein:

Figure 1 is a view showing the threshold lock

positioned in locking position in combination with a door and threshold with parts broken away and the threshold shown in section.

Figure 2 is a cross-section through the outer end of the threshold lock taken on line 2-2 of Figure 1.

Figure 3 is a sectional plan on line 3-3 of Figure 1, showing the door in section and illustrating the threshold locking elements in the position of locking the door closed.

Referring now to the drawings, wherein like reference characters indicate corresponding parts, the threshold lock of this invention includes the horizontal bar 10, an outer locking element or base 11 positioned below and adjacent one end of the bar adapted to bear against a supporting surface adjacent the threshold 20, the bar 10 being secured to the base 11 by means of a hinge plate 13, and a padlock 12.

The bar 10 is formed of a flat strip having an upwardly extending stop 14 with a thumb screw 15 threaded therein and a chain 17, having a spring-style snap closure element 18 at the outer end, is mounted in an opening 16 in the end of the stop. The inner end of the bar 10 is also provided with a vertically arranged thumb screw 19 by which the elevation of the inner end of the bar may be adjusted in relation to the threshold 20. The bar 10 extends straight through under a door 21, as shown in Figure 1, and the outer end is provided with a plurality of elongated slots 22 extending transversely across the outer portion thereof.

The outer end of the bar 10 is positioned on the upper surface 23 of the base 11 which is provided with a slot 24, and the base is positioned wherein the slot 24 is registerable selectively with one of the slots 22 so that a spline 25 on the under surface of the plate 13, which is hinged to the base element 11 by a hinge 26, extends through both of the slots to secure the locking element 11 in place. The base 11 is provided with a staple 27 that is positioned to extend through a slot 28 in the end of the plate 13, and with the bail of a padlock 12 secured through the staple, the locking element 11 will be positively locked in position on the outer end of the bar 10, wherein the door will be locked.

The threshold lock of this design may, therefore, be installed in the locking position on a threshold 20 by inserting the slot-containing end of the bar 10 underneath the door 21. In the inserted position, the chain 17 is no longer utilized, as clearly shown by referring to Figure 3 of the drawing. The vertically arranged thumbscrew 19 is then rotated to elevate the inner end of the bar with respect to the threshold, the lower end of the thumbscrew 19 engaging the adjacent portion of the supporting surface for the threshold 20 and the base 11. The stop 14 is then brought into engagement with the inner face of the door 21 to thereby limit the movement of the door inwardly. The slot-containing end of the bar 10 is supported

on the base 11 such that one of the slots in the bar 10 is in registry with the slot 24 provided in the base 11. The hinge plate 13 which carries a spline 25 is moved toward the base 11 until the spline 25 extends downwardly through the registering slots in the bar 10 and the base 11. The plate 13 is then locked in its position of movement with the spline 25 extending through the slots by means of the padlock 12 and the staple 27. Accordingly, the triangular shaped element 29 is fixedly held in a position such that it bears against the outer surface of the door 21 to thereby limit the movement of the door outwardly. Accordingly, the door 21 is held in a fixed position with respect to the threshold 20 and the base 11. The device, as illustrated, may be used without attaching the parts to the door, threshold, or floor, and may be withdrawn from its inserted position underneath the door and dependingly supported by the chain 17 which is detachably supported upon the knob of the door.

It will be understood that modifications may be made in the design and arrangement of the parts, if required, without departing from the spirit of the invention.

I claim:

1. A door lock for a swingable door having a raised threshold, comprising a bar having opposite ends, said bar being freely insertable between said door and threshold to dispose said ends beyond opposite sides of said door and threshold, upwardly directed stop means on each end of said bar for engaging opposite sides of said door, downwardly directed stop means on each end of said bar for engaging opposite sides of said threshold, one of said upwardly directed stop means being movable to and from an operative position in the path of said door and an inoperative position out of the path of said door, and means for locking said last named stop in said operative position.

2. A door lock for a swingable door having a raised threshold, comprising a bar having opposite ends, said bar being freely insertable between said door and threshold to dispose said ends beyond opposite sides of said door and threshold, one end of said bar having upwardly and downwardly directed stops engageable with like sides of said door and threshold, a locking base including upwardly and downwardly directed stops engageable with the opposite sides of said door and threshold, and means for releasably locking said base to the other end of said bar.
